UNITED STATES PATENT OFFICE.

GEORGE MORTON, OF LYNN, AND ALBERT J. LYONS, OF SAUGUS,
MASSACHUSETTS.

DESIGN FOR A HEEL-COUNTER FOR BOOTS OR SHOES.

SPECIFICATION forming part of Design No. 29,750, dated November 29, 1898.

Application filed October 22, 1898. Serial No. 694,346. Term of patent 14 years.

To all whom it may concern:

Be it known that we, GEORGE MORTON, of Lynn, and ALBERT J. LYONS, of Saugus, in the county of Essex and State of Massachusetts, have invented and produced a certain new and original Design for a Heel-Counter for Boots or Shoes, of which the following is a specification, reference being had to the accompanying drawings, forming a part thereof.

10 Of the drawings, Figure 1 represents a perspective view of a heel-counter, showing our design. Fig. 2 represents a bottom plan view of the same. Fig. 3 represents a section on line 3 3 of Fig. 2. Fig. 4 represents a section 15 on line 4 4 of Figs. 2 and 3.

As shown in the drawings, the leading or material feature of our design consists in the curved portion 2 3, that intervenes between the body portion α and flange α' of the counter. In any vertical section of the counter

the outer and inner surfaces of the curved portion 2 3 are continuations of the curvature of the outer and inner surfaces of the body portion α and join the surfaces of the flange α' , as shown in Figs. 3 and 4, the said curved portion extending inwardly under the body portion along the entire length of the counter and giving the lower portion of the counter a graceful curvature conforming to that of the heel. 25

We claim—

The design for a heel-counter for boots and shoes substantially as shown and described.

In testimony whereof we have affixed our signatures in presence of two witnesses.

GEORGE MORTON.
ALBERT J. LYONS.

Witnesses:

ISRAEL A. NEWHALL,
RUFUS KIMBALL.
